US0D1017165S

(12) **United States Design Patent** (10) Patent No.: **US D1,017,165 S**
Given et al. (45) Date of Patent: ** Mar. 5, 2024

(54) **CONTAINER LINER**

(71) Applicant: **Bercom International, LLC**, Chanhassen, MN (US)

(72) Inventors: **Jeff Given**, St. Paul, MN (US); **Mark Bergman**, Minnetonka, MN (US); **Jeff Waffensmith**, North Oaks, MN (US); **Matt Leyden**, St. Paul, MN (US)

(73) Assignee: **Bercom International, LLC**, Chanhassen, MN (US)

(**) Term: **15 Years**

(21) Appl. No.: **29/827,950**

(22) Filed: **Feb. 23, 2022**

(51) LOC (14) Cl. **07-05**

(52) U.S. Cl.

USPC **D32/54**

(58) **Field of Classification Search**

USPC D32/45, 53, 53.1, 54, 1

CPC B44D 3/12; B44D 3/123; B44D 3/128; B65D 25/14; B05B 11/0037; B05B 7/2478; B05B 7/2408

(57) **CLAIM**

The ornamental design for a container liner, as shown and described.

DESCRIPTION

FIG. 1 is a perspective view of a container liner; FIG. 2 is a right side view of the liner of FIG. 1; FIG. 3 is a left side view of the liner of FIG. 1; FIG. 4 is a back view of the liner of FIG. 1; FIG. 5 is a front view of the liner of FIG. 1; FIG. 6 is a top view of the liner of FIG. 1; and, FIG. 7 is a bottom view of the liner of FIG. 1. The dashed lines showing portions of the container liner in the drawings form no part of the claimed design.

1 Claim, 5 Drawing Sheets
